UNITED STATES PATENT OFFICE.

JOSEPH P. B. RAREY, OF KOKOMO, INDIANA, ASSIGNOR OF ONE-HALF TO
DANIEL RAREY, OF SAME PLACE.

GATE.

SPECIFICATION forming part of Letters Patent No. 295,428, dated March 18, 1884.

Application filed August 11, 1883. (No model.)

To all whom it may concern:

Be it known that I, JOSEPH P. B. RAREY, a citizen of the United States, and a resident of Kokomo, in the county of Howard and State of Indiana, have invented certain new and useful Improvements in Gates; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved gate. Fig. 2 is a front view of the same, and Fig. 3 is an end view.

Similar letters of reference indicate corresponding parts in all the figures.

My invention has relation to that class of gates which are operated by the wheel of a vehicle striking a swinging bail journaled in the roadway; and it consists in the improved construction and combination of parts of a sliding gate operated in this manner, as hereinafter more fully described and claimed.

25 In the accompanying drawings, the letters A indicate two posts at one side of the gateway, between which the gate slides.

B are two posts, to which the inner ends of the planks inclosing the gate, when drawn in, and the bar upon which the inner end of the gate slides, are fastened; and C is the abutting-post upon the other side of the gateway.

D is a rectangular frame placed in the roadbed at a level with or slightly below the same, upon which are fastened the bearings E, in which turn the straight portions of the bails F, which are operated by the wheels, and of the bails G, which are operated by the wheel-operated bails, and which operate the gate.

40 The wheel-operated bails consist of a smaller bail, H, against which the wheel of the vehicle strikes, and a larger bail, I, which straddles the gate-operating bail, and is placed at right angles to the same. The end of the rock-shaft or 45 rocking straight portion of the bail forms a crank, J, upon which is hinged a swinging weight, K, which serves to keep the bails in an upright position; and there is one bail at each side of the gate, one serving to open the 50 same, and the other to close it again.

The gate-operating bail consists of a straight rock-shaft, L, which forms a double crank, M, at its middle near the gate, and two bails, N and O, upon each side of the gate, which are curved slightly in opposite directions, the bails 55 of each pair standing in planes nearly at right angles to each other, and at angles of nearly forty-five degrees to the plane of the central crank. The two bails of each pair are at such a distance apart that when the wheel-operated 60 bails are tilted the inner bail will bear down upon one of them, tilting the same down.

The gate consists of the outer portion, P, which bars the gateway, and which may be of any desired construction, rails, paling, or wire 65 being used in its construction. The outer vertical post, which bears against the abutment-post, is provided with an upwardly-pointing catch, Q, which fits into a long recess, R, in the latter, provided with a slotted catch-plate, which 70 prevents the hooked catch from being withdrawn, except by pushing it down in the slot. A bar or rail, S, forms an extension of the top rail of the outer portion of the gate, and projects in between the posts A A and B B, forming 75 with an upright post, T, and a brace, U, the inner portion of the gate. A rail, V, is fastened between the upper ends of the two pairs of posts, between which the gate slides, and a roller, W, is journaled in a bail, X, upon the 80 top of the central upright post, T, and travels upon the upper surface of the said rail, while a similar roller, Y, is journaled between the lower ends of an upright bail, Z, which straddles the rail, and is fastened to the inner end 85 of the gate, the roller traveling against the under side of the rail. A connecting-arm, a, is hinged at one end to the upper rail of the inner portion of the gate, near to, but a short distance to the rear of, the central post, and is hinged at its other end to the long end of a lever, b, which is pivoted upon a horizontal rail, c, fastened at its end to the lower portions of two of the two pairs of posts between which the gate slides, and to the lower shorter end of 90 which is hinged a connecting-rod, d, the other end of which is hinged to the central double crank upon the gate-operating bails.

It will now be seen that when a vehicle passes toward the gate, one of the wheels will strike 95

the wheel-operated bail, tilting it, which will cause the bail upon its inner end to be tilted inward, pressing down the inner bail upon the gate-operating bail-shaft, which again will tilt 5 the said shaft and bail, and the double crank with it, forward toward the gateway, drawing the lower end of the lever in that direction, which causes a draw, in an upward and rearward direction, upon the connecting-rod hinged 10 to its upper end, which draw is communicated to the gate through the said rod, raising its inner end, and thereby releasing the catch and drawing it in. When, now, the vehicle has passed through the gate, its wheels will strike 15 the bail upon the other side of the gate, tilting it, which will cause the gate-operating rock-shaft to return to its old position, closing the gate.

Having thus described my invention, I claim 20 and desire to secure by Letters Patent of the United States—

1. The combination of two rock-shafts parallel with the gate, each having a bail adapted to be tilted by a vehicle-wheel, a bail near its 25 inner end in the same plane as the former, and a weight upon its end keeping it upright, with a rock-shaft parallel with the roadway, having two curved bails at each end at right angles to each other, and connecting means for operating 30 a gate, one wheel-operated shaft being at

each end of the gate-operating shaft, as and for the purpose shown and set forth.

2. The combination of an abutment-post having a slotted catch-plate, a gate sliding between two sets of posts, having an upwardly-hooked catch at its abutting end, and a roller at its center rolling upon the upper side, and a roller at its end traveling upon the lower side of a horizontal rail, a connecting-rod hinged to the gate to the rear of its center, a lever 40 having the said connecting-rod hinged to its upper longer end, a connecting-rod hinged to the lower short end of the lever, a rock-shaft having a pair of divergently-curved bails at each end, the bails in each pair being at right 45 angles to each other, and a double crank, to which the connecting-rod is hinged, and a pair of rock-shafts having bails adapted to be operated by a vehicle-wheel, bails straddling the rock-shaft between each pair of curved bails, 50 and weights at their ends keeping the bails upright, as and for the purpose shown and set forth.

In testimony that I claim the foregoing as my own I have hereunto affixed my signature in 55 presence of two witnesses.

JOSEPH P. B. RAREY.
